(57) **CLAIM**

The ornamental design for a three dimensional target training mannequin, as shown and described.

DESCRIPTION

FIG. 1 is a top perspective view for a three dimensional target training mannequin showing my new design;
FIG. 2 is a front side view thereof;
FIG. 3 is a left side view thereof;
FIG. 4 is a rear side view thereof;
FIG. 5 is a left side view thereof;
FIG. 6 is a bottom side view thereof; and,
FIG. 7 is a top view thereof.

The ornamental design which is claimed is shown in solid lines in the drawings. The broken lines are for illustrative purposes only and form no part of the claimed design. The broken line shown in FIGS. 1 through 7 is included for the purpose of illustrating portions of the three dimensional target training mannequin and forms no part of the claimed design.

1 Claim, 4 Drawing Sheets
